US00D998730S

(12) United States Design Patent (10) Patent No.: US D998,730 S
Baumann et al. (45) Date of Patent: * Sep. 12, 2023

(54) EXERCISE BAR

(71) Applicant: Procreate Brands LLC, Ferndale, WA (US)

(72) Inventors: Scott Baumann, Anacortes, WA (US); Edwin Cheong, Bellingham, WA (US)

(73) Assignee: Procreate Brands, LLC

() Term: 15 Years

(21) Appl. No.: 29/768,972

(22) Filed: Feb. 2, 2021

(51) LOC (14) Cl. 21-02

(52) U.S. Cl.

USPC D21/679

(57) CLAIM

The ornamental design for an exercise bar, as shown and described.

DESCRIPTION

FIG. 1 is a perspective view of the exercise bar of the present invention;

FIG. 2 is a front elevation view of the exercise bar, wherein the rear elevation view is a mirror image thereof;

FIG. 3 is a top plan view of the exercise bar;

FIG. 4 is a bottom plan view of the exercise bar; and,

FIG. 5 is a side elevation view of the exercise bar, wherein the opposite side elevation view is a mirror image thereof.

1 Claim, 3 Drawing Sheets
